CLAIM

The ornamental design for a pet bowl, as shown and described.

DESCRIPTION

FIG. 1 is a top perspective view of a pet bowl showing our new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view taken from circle 9 in FIG. 1;

FIG. 10 is an enlarged view taken from circle 10 in FIG. 2; and,

FIG. 11 is a perspective view thereof in a disassembled state. The dash-dash broken lines in the drawings illustrate the portions of the pet bowl that form no part of the claimed design.

The dot-dash broken lines in the drawings depict the boundaries of the enlarged views that form no part of the claimed design.
